UNITED STATES PATENT OFFICE.

WILLIAM APPLETON FERREE, OF BROOKLYN, NEW YORK, ASSIGNOR TO
SAMUEL P. FERREE, OF SAME PLACE.

DESIGN FOR A CASE FOR VENDING-MACHINES.

SPECIFICATION forming part of Design No. 24,426, dated June 25, 1895.

Application filed March 9, 1895. Serial No. 541,196. Term of patent 14 years.

To all whom it may concern:

Be it known that I, WILLIAM APPLETON FERREE, of Brooklyn, Kings county, New York, have invented a certain new and original Design for Cases for Vending-Machines, 5 of which the following is a specification.

The accompanying drawing is a perspective view of a vending-machine, showing my design, and attention is called thereto in connection with the following description, reference-letters being employed to designate the several features of the design.

A is the case which is cylindrical in general shape with squared ends.
15 B is the back of the case and C the front, and at the top is an extension having the ap-

pearance of a hinge. Near one end is an encircling line which divides the case vertically and gives the appearance of a short section D, joined to a long section. In the portion 20 which appears as the long section is an open panel e of rectangular form, and in the short section D is an open panel f of rectangular form but smaller than the open panel e.

What I claim is—

25 The design for a vending machine as herein shown and described.

WM. APPLETON FERREE.
